ABSTRACT

A solid bevel gear with integral solid shaft is provided as a blank and a core is extruded from this blank by means of an extrusion punch acting through the shaft end of the blank, using a die that supports the bevel gear in contour fitting relation as to the teeth and having a bore of diameter smaller than the punch through which the core is extruded. The core is subsequently removed.

METHOD FOR MAKING HOLLOW BEVEL GEARS WITH INTEGRAL HOLLOW SHAFT

BACKGROUND OF THE INVENTION

The present invention relates to a process of making bevel gears by means of metal working. The gear to be made is to have a body having configuration of a hollow truncated cone with a hollow shaft extending from the larger axial surface of the cone. More particularly, the invention relates to improvements in such processes wherein the gear is made through cold working a blank so as to obtain the desired configuration, and wherein the teeth extend from the frusto-conical body.

Bevel gears are used, for example, in the art of automotive engineering and here, particularly, in the gearing for the rear axle. The bore through the shaft receives that axle and is usually provided with splines. In view of the rather complex configuration of such gear, it seems obvious to make the basic body configuration first through conventional cold working, and to form the teeth separately; e.g., through press working.

Developing the latter thought further, one could, for example, start with a cylindrical blank which has been upset on one side to obtain a conical configuration. Then a bore is made through shallow forming and piercing. Finally, teeth are pressed into and from the cone. To proceed along this line means to follow the state of the art. However, bevel gears of satisfactory quality cannot be made through this application of conventional principles.

In order to fill completely the teeth-defining cavities in the die, the press working and extrusion process must proceed from the small diameter of the cone. Thus, upon planning production, the changes in configuration leading from the blank to the final bevel gear must not occur in an arbitrary sequence. Rather, the following rules must be observed:

The intermediate product used as blank for the tooth forming process must permit filling of the bevel gear die in direction from the small diameter. Thus, this particular blank must not have a bore. If this intermediate blank has already an axial bore, the material will flow radially outwardly as the press ram or punch advances. Consequently, the blank will be deformed to have an outwardly bulging configuration resulting in an overlap at the bore during repressing the teeth. As the dimensions and tolerances of the already completed teeth must be maintained, subsequent forming steps must not move material into the region of these teeth. However, precisely that does occur when the hollow shaft portion is made through inverted extrusion whereby the teeth have to be held in a toothed die element. Therefore, it was previously necessary to make the bore subsequent to the cold working process of the gear and by means of cutting, such as drilling. Obviously, bevel gear with long shafts are very expensive to make in this manner and the process is also quite time consuming.

DESCRIPTION OF THE INVENTION

It is an object of the present invention to make hollow bevel gears with integral hollow shaft by means of a process which is more economical than the known methods as previously practiced. It is a particular object of the invention to make bevel gears with integral hollow shaft by means of cold working process that does not require machining in spite of the relatively complex configuration.

In accordance with the present invention, it is suggested to provide a bevel gear first through cold working, such as extrusion molding, but in solid configuration and with a solid integral shaft extending from the side with larger diameter of the gears. Subsequently, a bore is formed in the gear and shaft in that a core is extruded, beginning from the shaft end and as a direct extrusion process out of the gear through the front face of smallest diameter thereof, whereby the extruded core has slightly smaller diameter than the bore cold worked by the punch into the shaft. Thus, machining is not involved to obtain the bore, nor is there the drawback resulting from using hollow blanks.

For practicing the invention, a die is used having contoured cavity corresponding to the bevel gear teeth. The die has a bore beginning in the small diameter bottom of the die cavity, and having diameter smaller than the diameter of a punch acting from above for extruding a core from the bevel gear for obtaining the bore therethrough. Preferably, the die is provided with a conical extrusion shoulder where facing the punch. This shoulder was found to increase the life of the die, and it improves the extrusion flow conditions.

While the specification concludes with claims particularly pointing out and distinctly claiming the subject matter which is regarded as the invention, it is believed that the invention, the objects and features of the invention and further objects, features and advantages thereof will be better understood from the following description taken in connection with the accompanying drawings in which:

The FIGURE illustrates a die and punch for making a hollow bevel gear, showing the beginning of the process of bore making to the left, and showing a phase close to completion to the right of a central dividing line.

DESCRIPTION OF THE DRAWING

Proceeding now to the detailed description of the drawing, the left-hand position shows an intermediate product like blank 1 comprised of a body 2 of frusto-conical configuration with an integral, short shaft 3. Blank 1 has solid configuration and body 2 is already provided with teeth 4.

This blank 1 is placed into a die 5 having particularly a contour so as to matingly receive the teeth 4, crest, flank and root, in accurate contour fitting relation. A sleeve 7 serving as plunge guide is placed onto the die 5 to supplement the die 5 as far as shaft 3 is concerned. The sleeve tightly receives the shaft and accordingly covers the die 5 completely.

The die 5 is provided with a bore 8 in the bottom and where facing the small diameter front face of the bevel gears. The bore 8 has diameter smaller than an extrusion punch 6. Bore 8 has a conical shoulder 10 at its upper end and is continued down in a bore 11 of somewhat larger diameter.

In operation, plunger or punch 6 is lowered (right-hand side). The punch has diameter corresponding to the diameter of the bore to be made in blank 1. As the punch 6 engages the blank, and thereafter upon continued down movement of the punch, a core is extruded in that material in the interior of blank 1 flows out at the lower end of blank 1 and into bore 8. In essence, a pin-like core 9 is extruded from the blank and received in the bore 8 of equal diameter. As bore 8 is continued in a somewhat wider opening 11, friction of

the extruded core 9 is reduced. Core 9 is removed separately upon completion of extrusion.

Conical shoulder 10 improves the flow conditions from the blank into the core, and the shoulder also avoids damage to this upper edge of bore 8. As stated, bore 8 has somewhat smaller diameter than punch 6, and the resulting bore in shaft and gears. This is necessary, as otherwise the material would not flow but break off. It can readily be seen that the centrally limited extrusion process does not disturb the configuration of the teeth as they have been formed previously, and the teeth are contour fittedly supported in die 5.

The invention is not limited to the embodiments described above but all changes and modifications thereof not constituting departures from the spirit and scope of the invention are intended to be included.

I claim:

1. Method for making bevel gear with integral hollow

4
shaft extending from the larger diameter surface of a frusto-conical body from which extends the teeth of the gears, comprising the steps of:

making a bevel gear with integral solid shaft by means of cold working including making a frusto-conical body with bevel gear teeth; and extruding from the bevel gear as a blank, a core through the small diameter surface of the bevel, through operation of a punch of larger diameter than the extruded core and acting on and through the integral shaft to obtain a bore therein.

2. Method as in claim 1, using a supporting die having contour matching configuration for supporting the blank and having an aperture in the bottom smaller than the diameter of the extrusion plunger.

3. Method as in claim 2, using a die wherein said aperture has a bevelled shoulder.
